(Cl. D33—1)

To all whom it may concern:

Be it known that I, Vincent Francis Le Verne, a citizen of the United States, residing in Long Beach, county of Los Angeles, and State of California, have invented a new, original, and ornamental Design for a Book End, of which the following is a specification, reference being had to the accompanying drawing, forming part thereof.

In the drawing:

Figure 1 is a side elevational view of the book end showing my new design;

Figure 2 is a front elevational view of the book end.

I claim:

The ornamental design for a book end, as shown.

VINCENT FRANCIS LE VERNE.
